Primary Examiner — Steven J Czyz(74) *Attorney, Agent, or Firm* — Robert Hess; Hess Patent Law Firm(57) **CLAIM**

The ornamental design for an integral header panel with outward convex curvature, as shown and described.

DESCRIPTION

FIG. 1 is an isometric view of an integral header panel with outward convex curvature in accordance with my design.

FIG. 2 is a front view thereof.

FIG. 3 is a bottom view thereof.

FIG. 4 is a top view thereof.

FIG. 5 is a right side view thereof.

FIG. 6 is a left side view thereof; and,

FIG. 7 is a rear view thereof.

The broken lines depict portions of the article that form no part of the claimed design.

1 Claim, 5 Drawing Sheets(56)
